UNITED STATES PATENT OFFICE.

REES H. LEMMON, OF LOS ANGELES, CALIFORNIA.

PUMP BARREL.

Application filed March 22, 1926. Serial No. 96,486.

This invention relates to pump barrels and is more particularly directed to a pump barrel constructed so as to permit the same to be inserted within the ordinary well tubing or 5 fluid string as employed in the pumping of oil wells and in which barrel a pump plunger is adapted to be reciprocated, and which pump barrel is releasably supported within the fluid string at one end and packed against 10 the fluid string at the other end, and which pump barrel has a plurality of ports formed therein for permitting the pump fluid to flow or circulate from the pump barrel into the fluid string around the pump barrel so as 15 to maintain equal fluid pressure within the pump barrel so as to enable the use of a relatively thin pump barrel which may be inserted within the fluid string without materially decreasing the size or operative capacity of the oil well pump.

This application is in part a division of my copending application, Serial No. 65,315, filed October 28, 1925.

In the pumping of oil wells, due to the presence of sand, gas pressure and often rotary mud and the like, the pumps become "sanded up" so that it is necessary to remove the pump assembly from the well to replace the operating valves or to repair the pump assembly. 25 Many attempts have been made to provide a pump assembly that could be supported within the well so that when it is required to remove the pump assembly or the working or standing valves thereof, it is only required 30 that the sucker rods which operate the pump plunger need be withdrawn from the well. These attempts have, for the most part, been partially successful but have been directed to the provision of means for withdrawing 35 from the well only the pump plunger and the operating and standing valves without provision for the removal of the pump barrel from the well and without the removal of the tubing or fluid string, to the end of which 40 such pump barrel has been suspended.

It is therefore an object of this invention to provide a pump barrel which is adapted to be mounted within the well tubing or fluid string and which pump barrel may be 45 removed or withdrawn from the well on removal of the sucker or pump rods from the well, together with the standing, operating valves and pump plunger of the oil well pump assembly.

Another object of this invention is to provide an oil well pump barrel which may

be inserted within a fluid string of an oil well and in which pump barrel means are provided for equalizing the fluid pressure on the interior and exterior of the pump 60 barrel so that a relatively thin pump barrel may be employed without danger of the same collapsing, and which relatively thin pump barrel will be adapted to accommodate a pump plunger of such size as not to 65 materially reduce the operating capacity of such an oil well pump over that employed in the pumping of wells using the same size tubing or fluid string which support at their lower end or from the lower end of 70 which is suspended the pump barrel.

Other objects and advantages of this invention will be apparent from the following detailed description of a preferred embodiment thereof as illustrated in the accompanying drawings, in which drawings:

Figure 1 is a side elevation partly in vertical section of an oil well pump plunger embodying this invention.

Figure 2 is an enlarged sectional side elevation of the lower portion of the oil well pump illustrating the anchor means provided for releasably supporting the pump plunger within the fluid string.

Figure 3 is a sectional side elevation of 85 the upper portion of the oil well plunger broken away from Figure 2 and illustrating the means provided for equalizing the fluid pressure within and without such pump plunger.

In the preferred embodiment of this invention illustrated in the accompanying drawings, 1 illustrates a casing which is of any desired or preferred construction and is supported within the well in a manner 90 well understood in the art. A fluid string or tubing 2 is mounted concentrically within the casing 1 and may likewise be of any desired or preferred construction. Suspended from the lower end of the tubing 2 is an annular sleeve 3, which annular sleeve 3 is secured to the lower section of the tubing 2 by means of a collar 4. The anchor sleeve 3 is of reduced diameter to a point near its upper end where the same is provided with 100 a tapered seat 5.

A pump barrel 6 of relatively thin metal, such as steel, is mounted concentrically within the tubing 2 and is provided at its upper end with an expandible packing member 7 110 which may be of any desired or preferred construction, one form of which is specifically

described and claimed in my copending application, Serial No. 65,815. The expandible packing member 7 being for the purpose of packing the barrel 6 outward against the fluid string 2 so as to maintain a fluid tight connection between the barrel 6 and the tubing 2 at or near the upper end so as to prevent the liquid in the pump, such as the oil, from flowing back into the well after the same has been pumped through the barrel 6 around the exterior thereof.

The barrel 6 is threaded at its lower end to a sleeve 8, in which sleeve 8 a pin 9 is secured, which pin 9 and sleeve 8 provide a cage for the standing valve ball 10. The standing valve ball 10 is mounted on a seat 11 which may be of any desired or preferred construction. A coupling member 12 is secured to the sleeve 8 at its upper end and to a barrel anchor 13 at its lower end. The barrel anchor 13 has at its lower end a tapered section 14 adapted to seat upon the tapered seat 5 formed at the upper end of the anchor sleeve 3. From the tapered portion 14, the anchor member 13 is of reduced exterior diameter and fits within the anchor sleeve 3 and is provided at its lower end with an expandible ring member 15 which is adapted to engage the lower tapered end face 16 of the anchor sleeve 3 so as to latch the pump barrel 6 in position within the fluid string 2 and prevent relative longitudinal movement of the fluid string 2 during the operation of the oil well pump. The expandible ring 15, being engaged from a tapered end face 16 of the anchor sleeve 3, also permits the removal of the pump barrel 6 from the well without necessitating the removal of the fluid string 2 and the anchor sleeve 3.

A pump plunger 17 is mounted within the pump barrel 6 and is supported by rods 18 and adapted to be reciprocated within the pump barrel 6 by means connected at the upper end of the pump rods 18. The construction and operation of which pump barrel 17 is specifically disclosed and claimed in my copending application, filed March 22, 1926, Serial No. 96,485.

In order to permit the use of a relatively thin pump barrel 6, means are provided for equalizing the external and internal pressure on the pump barrel 6, which means preferably comprise a plurality of ports 19 formed in the pump barrel 6 preferably at or near the upper end thereof so as to permit the pump oil or liquid to flow into the fluid string 2 around the pump barrel 6 so that during all pumping strokes of the plunger 17, the pressure on the exterior and interior of the barrel 6 will be equalized and thereby prevent collapsing of the pump barrel 6 and the use of a relatively thin barrel in formation of the barrel 6. The provision of the extremely thin pump barrel 6 and the means for equalizing the pressure upon the exterior and in-

terior thereof is an extremely important feature of this invention as it enables the use of an insertible pump barrel within the fluid string or well tubing 2, which pump barrel 6 supports the entire pump assembly and may be withdrawn with the entire pump assembly from the sucker rods 18 when it is desired to repair any part of the pump assembly. It is also extremely important, in the employment of an inserted pump barrel, that the same be relatively thin so as not to decrease the capacity of the pump which can be employed in a given size fluid string 2.

Having fully described a preferred embodiment of my invention, it is to be understood that I do not wish to be limited to the exact details herein set forth, which may obviously be varied without departing from the spirit of my invention as set forth in the appended claims.

I claim:

1. In an insertable well pump, the combination of a fluid string; a pump barrel having a plunger mounted within said string so as to provide an annular space between said string and said barrel, means interposed between said string and said barrel at its upper end and for sealing said annular space from the space within said string and above said barrel, and ports in said barrel below said sealing means placing the space on the discharge side of the plunger in communication with said annular space to permit the pumped fluid to flow outward around said barrel and below said sealing means.

2. In an insertable well pump, the combination of a fluid string, a pump barrel having a plunger mounted within the fluid string so as to provide an annular space between said string and said barrel, means expansible at will interposed between said string and barrel at its upper end for sealing said annular space from the space within said string and above said barrel, and ports in said barrel below said means placing the space on the discharge side of the plunger in communication with said annular space to permit the pumped fluid to flow outward around said barrel and below said means.

3. In an insertable well pump, the combination of a fluid string having a seating shoe, a pump barrel having a plunger mounted within the fluid string so as to provide an annular space between said string and said barrel, a seat at the lower end of said barrel supported on said shoe to seal the annular space at its lower end, means interposed between said string and said barrel at its upper end for sealing said annular space from the space within said string and above said barrel, and ports in said barrel intermediate said means and said seat placing the discharge side of the plunger into communication with said annular space to permit the pumped fluid to flow outward around said barrel.

4. In an insertable well pump, the combination of a fluid string having a seating shoe, a pump barrel having a plunger mounted within the fluid string so as to provide an annular space between said string and said barrel, a seat at the lower end of said barrel resting on said shoe and supporting said barrel to seal the annular space at its lower end, means 5 expandible at will interposed between said string and said barrel at its upper end for sealing said annular space from the space within said string and above said barrel, and ports in said barrel intermediate said means and said seat placing the space on the discharge side of the plunger in communication with said annular space to permit the pumped fluid to flow outward around said barrel. 15

Signed at Los Angeles, California, this 12
day of March, 1926.

REES H. LEMMON.
